United States Patent Office.

JOSEPH STOKES AND JOHN BROUH, OF TRENTON, NEW JERSEY.

Letters Patent No. 80,573, dated August 4, 1868.

IMPROVEMENT IN WATER-BOSHES FOR PUDDLING-FURNACES.

The Schedule referred to in these Letters Patent and making part of the same.

TO ALL WHOM IT MAY CONCERN:

Be it known that we, JOSEPH STOKES and JOHN BROUH, of Trenton, in the State of New Jersey, have invented a new and useful Improvement in the Construction of Water-Boshes for Puddling-Furnaces; and we do hereby declare that the following is a full, clear, and exact description thereof, reference being had to the accompanying drawings, making part of this specification, in which—

Figure 1 is a plan.

Figure 2, an elevation with part in section, taken at the line A a of fig. 1.

Figure 3, a section taken at the line B b of fig. 1, and

Figures 4 and 5, separate views of the discharging part of the furnace.

The same letters indicate like parts in all the figures.

The nature of our invention consists in constructing puddling-furnaces with a hollow bosh in one or more parts, of such form and construction that a current of water may be maintained within the bosh, through, under, and around the bottom of the furnace, or any part of the bottom thereof, in connection with or independent of a current of water within and around the bridge or bridges and jambs of the furnace.

We are aware that water-boshes have been heretofore used, but they have been so constructed as to protect imperfectly only the furnace-bridges and jambs; but the peculiar advantage of our improvement is such that while the bridges and jambs of the furnace are protected as heretofore, and prevented from being wasted and destroyed by the heat, an equal and efficient protection is afforded to the bottom of the furnace, and especially to the lower part of the fettling or lining of the bridges and jambs by the cooling agency of the current of water maintained within the bosh, under and around the bottom of the furnace.

In puddling-furnaces heretofore in use, a large amount of iron ore of the best quality has been employed, at considerable expense, for fettling or lining the bridges and jambs.

To avoid this expense, the ordinary iron water-bosh has been introduced without lining, but the excessive cooling effect produced thereby upon the iron introduced to be puddled, has been found to be unfavorable for the production of a good quality of iron, and often a rapid waste and destruction of the material of the bosh have occurred.

If, to avoid this excessive and unfavorable cooling effect, the usual lining be used upon the surface of the bosh exposed to the iron to be puddled, no advantage is gained over the usual brick bridge; but, by the use of our improvement, by means of which a current of water is maintained within the bosh, as already specified, a thinner fettling or lining may be employed in and upon the bridge and jambs of the furnace, without the rapid waste and destruction of the materials used for fettling or lining, that have heretofore taken place in consequence of the effect of the heat, and the chemical and mechanical action of the melted iron and cinder.

The following advantages result from the use of this improvement:

First, the size of the furnace may be considerably reduced, as the usual thick fettling is dispensed with, and the cost of material and labor in erection is thereby lessened.

Second, the size of fire-grate may be diminished, and a saving of fuel effected.

Third, a thinner fettling, at less expense, may be employed, with equally favorable results in the yield of iron.

Fourth, the rapid waste and destruction of the substances used for fettling or lining, by the action of the heat and of the melted iron and cinder, are prevented by the protecting action of the current of water circulating in the furnace-bottom within the bosh, as already specified, this protection being afforded particularly at the lower part of the fettling or lining, which has been heretofore least protected, and much exposed to waste and destructive action.

In the accompanying drawings, *a* represents the puddling-bottom, *b* the hollow bridge, and *c* the boshes, which are hollow, as represented at *d*, the hollow part extending some distance under the bottom, so as to afford protection at and along the junction of the boshes with the bottom, where the fettling is most exposed to the destructive action of the heat and cinder.

Suitable pipes are provided for the introduction and discharge of water, which should be caused to circulate through the hollow parts when the furnace is in action.

The hollow parts may be made continuous or in sections, but if made in sections, each section should be provided with an induction and an eduction-pipe.

It is deemed unnecessary to explain the construction of the bridge and other parts of a puddling-furnace, as that is well known to iron-masters.

The hollow of the boshes may be extended under the entire bottom, if desired, but we prefer to extend it no further than represented in the accompanying drawings.

What we claim as our invention, and desire to secure by Letters Patent, as an improvement in puddling-furnaces, is—

Making the boshes hollow, and the hollow to extend under the bottom for the passage of a current of water, substantially as and for the purpose set forth.

JOSEPH STOKES,
his
JOHN X BROUGH.
mark.
